ROOM THERMOSTAT

Alan W. Duncan, Itasca, Ill., assignor to Sears, Roebuck and Co., Chicago, Ill., a corporation of New York

Filed June 30, 1960, Ser. No. 61,166

Term of patent 7 years

(Cl. D52—7)

Fig. 1.

Fig. 2.

Fig. 3.

Fig. 1 is a front elevational view of a room thermostat embodying my new design.

Fig. 2 is a side elevational view thereof, and

Fig. 3 is a diametrical sectional view of same.

The essential features of my design reside in the full line portions.

I claim:

The ornamental design for a room thermostat, as shown and described.
